(57) CLAIM

The ornamental design for a table, as shown and described.

DESCRIPTION

FIG. 1 is a front right perspective view of a table according to the new design;

FIG. 2 is a rear left perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof;

FIG. 9 is a front right perspective view of a second embodiment of the table;

FIG. 10 is a rear left perspective view thereof;

FIG. 11 is a front elevational view thereof;

FIG. 12 is a right side elevational view thereof;

FIG. 13 is a left side elevational view thereof;

FIG. 14 is a rear elevational view thereof;

FIG. 15 is a top view thereof; and,

FIG. 16 is a bottom view thereof.

The broken lines in the drawings illustrate portions of the table that form no part of the claimed design.

The long dash-dot-long dash lines in the drawings represent a boundary of the claimed design and forms no part thereof. FIGS. 9–16 are shown with a symbolic break in its length and width. Any portion of the article between the breakaway lines forms no part of the claimed design.

1 Claim, 16 Drawing Sheets
